UNITED STATES PATENT OFFICE.

JOHN E. MITCHELL, OF ST. LOUIS, MISSOURI.

COTTON CLEANING AND SEPARATING MACHINE.

1,395,054.

Specification of Letters Patent. Patented Oct. 25, 1921.

Application filed January 17, 1921. Serial No. 437,651.

To all whom it may concern:

Be it known that I, JOHN E. MITCHELL, a citizen of the United States, residing in the city of St. Louis and State of Missouri, have 5 invented new and useful Improvements in Cotton Cleaning and Separating Machines, of which the following is a specification.

This invention relates to certain new and useful improvements in cotton cleaning and 10 separating machines and has special reference to a novel construction of dumping hull board. The broad object of the invention is to permit the separation and recovery of the maximum amount of cotton from bolls 15 and field cotton fed into the machine, by providing for the rapid discharge and removal from contact with the cotton and saw cylinder of the hulls, trash, and other waste products fed into the machine with the cotton 20 ton. In Patent No. 1,360,132 there is disclosed a construction wherein the space between a single hull board and the saw cylinder is periodically widened by moving the hull board away from the saw cylinder to 25 permit the discharge from the agitating chamber of all accumulated hulls and other waste products, and means are provided for shutting off the feed of the cotton to the agitating chamber slightly in advance of the 30 opening or discharge movement of the hull board. This, of course, is to prevent cotton being fed into the agitating chamber and discharged therefrom through the wide opening provided by the hull board. While 35 the machine of the patent referred to represents, in principle an advance in the art, it was found, nevertheless, that there were certain objections attendant upon its operation. One of these was a slight interference with 40 the uniformity of the feed; another is that when the feed is shut off, the saw cylinder takes the bulk of the load of cotton out of the working chamber quickly enough, but always leaves a considerable number of small 45 loose floating locks of cotton which the teeth of the saws are unable to take hold of unless they form part of the mass of a considerable quantity of cotton; and as a result, these small locks of cotton, which continue 50 to bounce around in the working chamber after the feed is shut off, will ultimately escape to the hull conveyer when the hull board is open.

These objections are overcome by the present construction in which a double hull board arrangement is used in connection

with a single saw cylinder, and means are provided for opening and closing in alternation, the two hull boards whereby the waste incident to the escape of the class of 60 cotton referred to is effectively prevented.

In addition to the general object of the invention above set forth, other objects relate to the novel construction and arrangement of parts, as hereinafter described and 65 pointed out in the claims.

In the accompanying drawings

Figure 1 is a cross-sectional view through a machine constructed according to my invention taken just inside of the frame at one 70 side of the machine, and showing the hull board construction with the coöperating cam shaft in cross-section;

Fig. 2 is a view in rear elevation of the hull boards and cam shaft, other parts of 75 the machine being omitted; and

Fig. 3 is a section taken at the opposite end of the cam shaft from that shown in Fig. 1, but showing the position of the hull boards reversed.

80

Referring now to the drawings, the numeral 1 indicates the casing of the machine having an opening in its top through which the bolls and cotton are supplied, the feed being controlled by the feed rolls 2. The 85 numeral 3 indicates a breaker cylinder which operates to break the bolls apart and move the mixed cotton and bolls to an opening 4 in the breaking chamber whence this product is removed by a picker roll 5. The 90 picker roll delivers the mixed cotton and bolls to an agitating chamber 6 in the lower part of which is rotated a saw cylinder 7. Rotating above and in proximity to the saw cylinder is a kicker roll 8 and below this 95 roll and rotating in proximity to the saw cylinder is a doffer roll 9. These parts are all shown in various prior patents and need not be more particularly described. The numeral 10 indicates a shaft which is rotated 100 in any suitable manner and mounted on either end of which are two cams 11 and 12 rotated by the shaft 10 in the direction indicated by the arrow in Fig. 1. The numeral 13 indicates a hull board which 105 is pivotally mounted at 14 above the cam shaft 10. On its under side, at either end, this hull board is provided with projections 15 which projections are designed to co-operate with the respective cams 12. Each 110 of cams 12 is provided with a cam shoulder 16 which is designed to coöperate with a

cam face 17 of the corresponding projections 15, and each of the cams 12 is further provided with a raised or working face 18 and reduced portions 19. In operation, when the shoulder 16 engages the cam faces 17 of the projections 15, the hull board 13 will be raised to the position shown in Fig. 3; that is to say, with the lower end of the hull board moved to its closest position with reference to the saw cylinder, and will remain in this position so long as the projections 15 ride on the raised portions 18 of the cam. When the projections 15 ride off of said raised portions and fall on to the reduced portions 19 of said cams, the hull board falls to the open position or that affording the widest opening between the saw cylinder and the lower end of the hull board, such position being shown in Fig. 1. Each of the cams 11 is provided with a cam groove 20 and normal working face 21. The numeral 22 indicates a hull board pivotally mounted at 23 below the cam shaft 10. Formed rigid with this hull board at either end are arms 24, each of which is provided with a roller 25 which is adapted to coöperate with the corresponding cams 11. In the rotation of the cams 11 when the rollers 25 are on the raised or working face 21 of cams 11, the hull board 22 will be in the raised or normal position shown in Fig. 1. When the grooves 20 move opposite the rollers 25, the latter enter said grooves and permit the hull board 22 to fall and thus widen the opening between the lower end of said hull board and the saw cylinder 7. This position of the hull board is shown in Fig. 3.

From the foregoing, it will be seen that the two hull boards alternate in their movements; that is to say, when the hull board 13 is in a lowered or discharge position, the hull board 22 will be in the raised or operative position. These positions are shown in Fig. 1. Conversely, when the hull board 13 is in the raised or operative position, the hull board 22 will be in the open or discharge position. This latter position of the hull board is shown in Fig. 3.

The opening between the lower edge of the upper hull board 13 and the saw cylinder 7 is indicated by the numeral 26 and the opening between the lower end of the hull board 22 and the saw cylinder is indicated by the numeral 27. The numeral 28 indicates a conveyer for removing hulls and waste products from the machine.

When the upper hull board 13 is in its raised or closed position, there is still space enough between the lower end of the board and the saw cylinder to permit the continual discharge of ninety per cent. or more of the hulls and trash through the opening 26, but this opening is not large enough to permit the escape of any cotton of value and,

of course, the large hulls and foreign substances cannot escape through this opening. When this upper hull board is permitted to swing back away from the saw cylinder to the position shown in Fig. 1 to widen the opening 26 to permit the discharge of the accumulated large hulls and other sizable foreign matter, some cotton will likewise pass through the opening; but during the time the upper hull board is in the open or discharge position, the lower hull board is in its closed position and will prevent the escape of such cotton through the opening 27, but at the same time permit the free and continuous discharge of most of the hulls which have passed through the opening 26, or been discharged through said opening by the movement of the hull board 13. As soon as the upper hull board is moved by the cams 12 to the closed position, then the lower hull board is opened to permit the discharge to the conveyer of the larger particles of hulls and trash.

The interval of time between the closing of the upper hull board and the opening of the lower hull board which is determined by the length of the operating face 21 of each of the cams 11, is sufficient to permit the saw cylinder to extract any cotton of value remaining in the accumulated mass between the two hull boards.

As in prior machines of this type, it will be understood that hull particles carried up by the cotton on the saw cylinder 7 are knocked back by the kicker roll 8 and the cotton is removed from the saw cylinder by the doffer roll 9 and discharged through the opening 29 in the casing.

While I have illustrated in the drawings a preferred means of operating the hull boards in alternation, it will be obvious that the broad idea of the invention is not limited to the special means described, and that other ways of manipulating the two hull boards to practice my invention could be used without departing from the spirit of my invention.

I claim:

1. In a machine of the class described in combination with the saw cylinder, an upper and a lower hull board coöperating therewith, and each of which defines the size of an opening past the saw cylinder, and means for alternately discharging products accumulating above the respective hull boards.

2. In a machine of the class described, in combination with the saw cylinder, an upper and a lower hull board coöperating therewith and the lower edge of each of which defines the size of an opening past the saw cylinder, and means for widening said openings in stages and in alternation.

3. In a machine of the class described in combination with a saw cylinder, an upper and a lower hull board coöperating there-

with and the lower edge of each of which defines the size of an opening past the saw cylinder, and means operating to lower the upper hull board away from the saw cylinder to discharge accumulated products upon the lower hull board while the latter hull board is maintained in a normal operative position, and then to return the upper hull board to normal position and to move the lower hull board to a discharge position, said means operating continuously to effect the alternate movements of the hull boards.

4. In a machine of the class described in combination with a saw cylinder, an upper

and lower hull board coöperating therewith, 15 and the lower edge of each of which defines the size of an opening past the saw cylinder, a rotatable cam shaft having cams thereon coöperating with the respective hull boards, said cams operating to alternately lower and 20 then raise one of said hull boards maintaining the other in normal position, thereafter to lower and then raise the latter hull board while maintaining the first hull board in operative position.

In testimony whereof, I have hereunto set my hand.

JOHN E. MITCHELL.
